UNITED STATES PATENT OFFICE

ROBERT WRAY MANNING, OF CLEVELAND, OHIO

ADVERTISING NOVELTY

Application filed July 24, 1931. Serial No. 552,953.

My present invention has reference to an advertising medium in the nature of a folder, of a size to permit of the same being transmitted through the mail and of a construction which will present different views upon the front and back thereof when in folded condition and still different views and scenes upon its opposite faces when opened and further wherein the construction is such that the folder can be reversely opened in a manner which is rather mysterious to the uninitiated and which, together with the mechanical features of its construction will capture and hold the interest of those who receive the folder.

A further object is the construction of an advertising folder which when opened one way will disclose the top and bottom strip of the central fold of one page and the central strip of the adjoining page and which when closed and opened in an opposite direction will have its reverse side present two panels, all of the display portions of the folder being provided with attractive illustrations as well as data relative to the device or materials advertised by the folder.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a face view of the blank from which the folder is formed.

Figure 2 is a similar view of the reverse face of the blank.

Figure 3 is a plan view of the blank to illustrate the portions thereof which are adhesively treated.

Figure 4 is a perspective view to illustrate the first step of the folding of the blank.

Figure 5 is a perspective view showing the blank folded with parts connected.

Figure 6 is a similar view looking toward the reverse face of the folder as disclosed by Figure 5.

Figure 7 is a sectional view approximately on the line 7—7 of Figure 5.

Figure 8 is a sectional view approximately on the line 8—8 of Figure 5.

As disclosed by Figures 1 and 2 of the drawings the folder is constructed from a single sheet of stiff paper or the like and is of rectangular formation. The sheet is centrally formed with a transverse fold line 1 and an equidistance therefrom with outer transverse fold lines 2 and 3, respectively. The distance between the fold lines 1 and 2 and 1 and 3 is equal to the distance between the fold lines 2 and 3 and the outer ends of the blank. At points equidistant from the edges of the blank the said blank is slotted longitudinally between the fold lines 2 and 3 and these slotted portions for distinction are indicated by the numerals 4 and 5. The panels 6 and 7 between the slits 4 and 5 of the fold lines 1, 2 and 3 have inscribed, painted or otherwise arranged thereon ornamental figures which may and preferably have reference to articles or materials to be advertised by the folder while the short panels above the slit 5 and what I will term the upper edge of the flange and which are indicated by the numerals 8 and 9, respectively, have printed thereon headings relative to the advertising matters. The lower panels 9' and 10 between the lower edge of the blank and the slit 4 have imprinted thereon reading matter relative to the advertisement while the end panels 11 and 12 have inscribed thereon matter relative to the advertisement or ornamental figures as disclosed by Figure 1 of the drawings. The above mentioned illustrations and printed matters are arranged on what I, for distinction will call the front face of the blank, which is illustrated by Figure 1 of the drawings. The rear face of the blank is illustrated by Figure 2 of the drawings and the upper and small panel, corresponding to the panel 9 and indicated by the numeral 13 is provided with an illus-

95

trative or advertising matter which is true with respect to the lower short panel 14, directly opposite the panel 13, and such illustrations or advertising matter also appear on the upper corners at the rear of the panel 12, which in Figure 2 is indicated by the numeral 15. The panel 16 which is arranged directly to the rear of the panel 6 is also provided with illustrative or advertising matter, which is true with respect to the rear face 17 of the panel 11, the height of the advertising matter on the said face 17 being equal to the distance between the slits 4 and 5.

Figure 3 is a view similar to Figure 2 devoid of all illustrative material. In this figure it will be noted that the unprinted or blank panel 18, between the panels 16 and 15 is treated with an adhesive substance, and likewise that the narrow panels 19 and 20 below the panel 16 and between the short panel 14 and the panel or face 17 are also treated with an adhesive substance. The card or blank is first folded on the score line 1 and then on the score line 3, the adhesive on the face 18 being moistened and pressed against the blank on the face 15, thus adhesively connecting these parts. The short panels 13, 14, 19 and 20 are folded against each other and the adhesively treated faces 19 and 20 of the panels 9 and 10 are swung together on the full line 1 over the face 17 and above the illustrative or advertising matter thereon and are adhesively secured to the said base or panel. When the folder has its pages or faces brought together and is in condition for mailing the panel 11 may and preferably does present the outer page or face of the folder and the panel 12 the rear face thereof, the panels 6 and 7 being folded together on the score line 1. The folder may be opened from either of its edges, and when opened in one direction will disclose the panels 6 and 7 and the short panels 9 and 10 and when opened in a reverse direction the faces 16 and 17 as well as the illustrations on the narrow panels 13 and 14 and the illustrations or advertising matter on the ends of the panel 15 will be brought to view.

The folder is of such construction that the opening thereof will mystify or puzzle the receiver of the folder and will thereby capture and hold his interest so that all of the advertising matter which, of course, includes the views or engravings will be carefully inspected by the receiver of the folder and thus the folder will fully accomplish its purpose as an advertising medium. The pictorial illustrations on the folder are artistic and the novelty of the construction of the folder is such that the same is not liable to be hastily discarded as is true with respect to most advertising folders. The folder is very apt to be kept as a puzzle or as a curiosity by the receiver who will doubtless hand the same to others and note with interest the manner in

which attempts are made to open or close the folder and such others will doubtless fully observe all of the advertising matter disclosed on the folder and is, therefore, a prospective purchaser of such articles.

The device is of an extremely simple construction and may be produced economically. The folder can be operated with interest by both children and others and the detail description of the device as herein set forth refers only to one practical embodiment thereof as I do not wish to be restricted to the number of slots or hinges employed in the construction or to the form that these shall take. The slots may be cut diagonally, at a curvature or a combination of both, and in some instances portions of the folder can be cut away to form the folder with a complete cutout portion. The holder, as stated, is primarily intended for use as an advertising piece but due to its unusual mechanical construction it is adapted to a variety of uses, such as greeting cards, correspondence cards, calling cards, business cards, etc. The device as previously inferred may be of any size and I do not wish to be restricted to the material employed as in some instances, when the folder is constructed on a large scale the same may be formed of wall board, bendable metal or the like.

Having described the invention, I claim:

1. A folder formed from a sheet of material, folded to provide a pair of outer and a pair of inner panels, the inner panels being slotted longitudinally between the fold lines of the outer panels to form a pair of outer strips and a central strip, and the outer strips thus provided being folded upon themselves and connected to one of the outer panels, and the central strips when folded upon itself being directed against and secured to the opposite outer panel.

2. A folder for the purpose set forth, having panels which are hingedly connected, and which afford outer or end panels and central panels, and said central panels having divided parts each of which is folded upon itself, said folded parts being oppositely directed and secured to the respective inner and outer panels.

3. A folder for the purpose set forth, comprising a substantially rectangular sheet divided by fold lines into a pair of outer and a pair of inner panels, and the inner panels having parts connected to the respective outer panels to permit of the folder being opened in opposite directions from either end thereof.

In testimony whereof I affix my signature.

ROBERT WRAY MANNING.
